United States Patent Office

Des. 188,208
Patented June 14, 1960

188,208

PLATE OR SIMILAR ARTICLE

Gerald S. Stone, Scarsdale, N.Y., assignor to Johnson Bros. (Hanley) Limited, Hanley, Stone-on-Trent, England, a company of Great Britain

Filed Oct. 20, 1959, Ser. No. 58,034

Term of patent 14 years

(Cl. D44—15)

The figure is a top plan view of a plate or similar article of conventional configuration showing my new design.

I claim:

The ornamental design for a plate or similar article, substantially as shown and described.
